Des. 211,958
Patented Aug. 13, 1968

211,958

PULL-TYPE WINDROWER

William D. Long, Hesston, and Richard E. Ten Eyck,
Wichita, Kans., assignors to Hesston Corporation, Inc.,
Hesston, Kans., a corporation of Kansas

Filed June 16, 1967, Ser. No. 7,495

Term of patent 14 years

(Cl. D40—1)

Fig. 3.

Fig. 4.

FIGURE 1 is a side perspective view of a pull-type windrower;

FIG. 2 is a perspective view of the side opposite to the side shown in FIG. 1;

FIG. 3 is a top front perspective view;

FIG. 4 is a rear perspective view;

FIG. 5 is a front perspective view; and

FIG. 6 is a top rear perspective view.

The dominant features of my design reside in the portions shown in full lines.

We claim:

The ornamental design for a pull-type windrower, as shown and described.
